UNITED STATES PATENT OFFICE.

WILLIAM F. DUCKWITZ, OF CLEVELAND, OHIO.

LOCK.

992,552.

Specification of Letters Patent. Patented May 16, 1911.

Application filed November 5, 1910. Serial No. 590,822.

To all whom it may concern:

Be it known that I, WILLIAM F. DUCKWITZ, a citizen of the United States, residing at Cleveland, in the county of Cuyahoga and State of Ohio, have invented a certain new and useful Improvement in Locks, of which the following is a full, clear, and exact description, reference being had to the accompanying drawings.

10 The object of this invention is to provide a very simple and efficient latch or lock for holding snugly together two members and preventing their relative movement.

One of the uses of my lock is for window sashes, the lock being adapted to be carried by the meeting rails and operating to draw them together and securely hold them. Such an embodiment of my lock requires but three pieces (in addition to the holding 20 screws) namely; the keeper, adapted to be secured to one sash-rail; a wedge-faced bolt, adapted to coöperate with the keeper, and a third member secured to the other sash-rail and adapted to retain the bolt while 25 allowing it to be tipped over from idle to active position and to be shifted while in the active position to tighten the engagement.

The drawings clearly illustrate my invention as applied to a sash lock.

Figure 1 is a vertical section through the meeting rails of the sash, showing the lock in engagement; Fig. 2 is a similar view, showing the lock in idle position; Fig. 35 3 is a plan of the lock engaged; Fig. 4 is a rear elevation of the lock engaged; Fig. 5 is a front elevation of the lock engaged; Fig. 6 is a perspective of the keeper; Fig. 7 is a perspective of the bolt; and Fig. 8 40 is a perspective of the clip retaining the bolt.

As shown in the drawings, A represents the bottom rail of the top sash and B the top rail of the bottom sash.

C indicates the keeper attached to the 45 rail A.

D indicates the bolt, and E the retaining member attached to the rail B and holding the bolt. The keeper and retaining member are secured by suitable screws F and G, respectively, or in any other manner, as 50 desired.

The keeper C, as shown, comprises a base plate c and a standard e^1 rising centrally therefrom and having a forwardly projecting jaw c^2 , the under surface of which is inclined, not only upwardly toward the

body of the standard, but lengthwise of the base. The standard, jaw and base plate are preferably one integral piece of metal.

The bolt D is preferably one integral 60 piece, but may be considered as having three portions, namely; the bail, or loop portion, d, the operating web or handle d^1 , and the wedge-portion d^2 . The upper face of the wedge-portion is inclined toward the base 65 of the member D in the same directions as the incline of the face of the jaw c^2 . The rear edge of the wedge is also preferably inclined toward the handle d^1 . The wedge d^2 is shorter than the bail by a distance 70 corresponding to the thickness of the portion of the clip which retains the bail. Accordingly, when the bolt is in one of its extreme positions the wedge may be beyond the keeper and adapted to be turned over 75 past it into position to be slid beneath the jaw.

The retaining member or clip for the bolt is indicated by E and consists of a base plate e adapted to be secured to the rail B, 80 and a loop in the form of an arched member e^1 , which rises from the plate e and then depends from that plate to a plane substantially alining with the bottom surface of the plate e. Accordingly, when the retaining 85 member E is in place on the sash, the lower surface of the arched member e substantially abuts the top of the rail B. This arched member straddles the bail d, thereby retaining the bolt on the sash B, but allowing it, not only to be turned toward and from the other sash, but shifted longitudinally of the sash rails to cause a tight engagement.

It will be seen at a glance that, in installing the parts, the keeper C is secured to the rail of the upper sash adjacent to the front edge thereof and the clip E is secured to the upper rail of the lower sash at the rear edge thereof opposite the keeper and with 100 the arch straddling the bail of the bolt.

Fig 2 shows the idle position of the parts, the bolt being carried by the retaining member E and the sashes operating independently of each other. To lock the sashes, it 105 is only necessary to turn the bolt over until its base rests on the plate e, the wedge-portion d^2 passing alongside of the jaw c^2 into alinement with the space beneath it, and then to move the bolt lengthwise so that its 110 wedge-portion comes into gripping contact with the inclined under face of the jaw c^2 .

By reason of the double incline of this under face of the jaw and on the upper face of the wedge, not only does the wedge bind tightly in the keeper, but the two rails A 5 and B are drawn snugly together. The tightness of this locking may be increased, if desired, by a hammer blow on the end of the bolt—the right hand end in the embodiment shown.

- 10 It will be seen that, while my lock is very simple in construction, it is peculiarly effective, in practice, holding the parts together with great snugness. Moreover, my lock is not only adaptable for usual hand 15 operation, but may be very conveniently employed in inaccessible places, as, for example, large windows where it is desired to operate the lock by means of a pole, rather than in the ordinary manner. In such an 20 installation, an ordinary window pole may turn the bolt over from the position shown in Fig. 2 to that shown in Fig. 1 and a blow from said pole on the end of the bolt will complete the locking.
- 25 Having thus described my invention, what I claim is:—

1. In a lock, the combination of a keeper having an inclined jaw, a bolt having a wedge coöperating with the jaw, and a retaining member for the bolt holding it to 30 allow it to be turned into and out of juxtaposition with the jaw and shifted longitudinally in engagement with the jaw.
2. In a lock, the combination, with a keeper, of a bolt having a bail, retaining means loosely engaging the bail whereby the bolt is held in a manner to enable it to be turned and also shifted, the bolt and keeper having complementarily inclined en- 35 gageable surfaces.
3. In a lock, the combination with a suitable retaining member, of a bolt having a bail loosely held by the retaining member, a handle portion and a wedge-portion, and a keeper having an inclined jaw coöperating with the wedge-portion.
4. In a lock, the combination, with a retaining member having a base plate and a loop, of a bolt having a bail slidable through 50 said loop and having a wedge-member, and a keeper having a jaw coöperating with the wedge-member.
5. In a lock, the combination, with a retaining member having a base plate and an arch, of a bolt having a bail slidable through 55

said arch and having a locking portion, a keeper having a jaw coöperating with the locking portion, the bail having a part of its length opposite said locking portion, and a part which is beyond said locking portion, 60 whereby the locking portion may be moved past the keeper-jaw and then slid longitudinally in engagement therewith.

6. The combination, with a suitable keeper and a suitable retaining member, of a bolt 65 having a bail coöperating with the retaining member, and a wedge coöperating with the keeper, the bail extending beyond the end of the wedge.

7. In a lock, the combination, with a keeper 70 having a jaw which is inclined on its under surface in two directions, a bolt having a correspondingly inclined wedge-portion, and a retaining member for the bolt allowing it to be turned and shifted longitudinally.

8. In a lock, the combination of a keeper having a base plate, a standard rising therefrom, a jaw projecting forwardly from the standard and having an under face which is inclined upwardly from the base toward the 80 standard and also inclined in the direction of the length of the base, a longitudinally shiftable bolt having a correspondingly inclined wedge-portion, and a retaining member for the bolt.

9. In a lock, the combination of a bolt having a bail, a wedge-portion and an intermediate handle portion, the wedge-portion extending diagonally upward from the lower plane of the bail portion and terminating 90 short of the length of the handle portion, a retaining device for the bolt and a keeper adapted to coöperate with said wedge-portion.

10. In a lock, the combination, with a keeper, a bolt coöperating therewith having a bail, and a retaining member to hold the bolt comprising a base plate and an arched portion rising therefrom and depending some distance from the base, whereby when 100 the retaining member is removed, the bolt is free but when in place the bolt is held loosely.

In testimony whereof, I hereunto affix my signature in the presence of two witnesses. 105

WILLIAM F. DUCKWITZ.
